UNITED STATES PATENT OFFICE.

RIES W. HAGGARD, OF HOLBROOK, KENTUCKY.

DESIGN FOR A CRADLE-FRAME.

SPECIFICATION forming part of Design No. 27,726, dated October 12, 1897.

Application filed January 29, 1897. Serial No. 621,243. Term of patent 14 years.

To all whom it may concern:

Be it known that I, RIES W. HAGGARD, a citizen of the United States, residing at Holbrook, in the county of Grant and State of Kentucky, have invented a new and original Design for Cradle-Frames, of which the following is a specification.

This invention relates to a new and original design for a cradle-frame; and it has for its object to provide a design of this character that shall be both useful and ornamental.

The leading feature of the design resides in rectangular scalloped upright end frame portions, each of which end frame portions comprises upper and lower horizontal cross-bars, a pair of parallel vertical standards connecting the cross-bars, and an inverted-V-shaped figure having its legs converge from the lower ends of the standards to the center of the upper cross-bar, and a pair of parallel horizontal scalloped base-bars connecting the lower cross-bars of the end frame portions.

A minor feature of the design resides in providing the vertical standards at their outer corners with a continuous series of elliptical scallops and at their inner corners with a regular series of spaced angular indentations or cuts, and also in providing said vertical standards with plain squared portions at their points of connection with the upper cross-bars, and spherical figures at their upper extreme ends.

A minor feature of the design resides also in providing the upper horizontal cross-bars of the end frame portions with spaced pairs of elliptical concavities in their upper corners and in providing the upper outer corners of the horizontal base-bars with a series of angular indentations.

In the drawings, Figure 1 is a perspective

view of a cradle-frame embodying the herein-described design. Fig. 2 is a vertical transverse sectional view thereof.

Referring to the accompanying drawings, the numerals 1 1 designate the rectangular upright end portions of the cradle-frame, and each of these upright end frame portions 1 comprises a pair of parallel vertical standards 2, upper and lower horizontal cross-bars 3 and 4, respectively, connecting said standards, and an inverted-V-shaped figure having its legs 4^a converge from the lower end of the standards 2 to the center of the upper cross-bar 3. The standards 2 are formed in their outer corners with a continuous series of elliptical scallops 5, and in their corresponding inner corners with a regular series of spaced angular indentations or cuts 6. In addition to the scallops and cuts 5 and 6, the standards 2 are formed, at their point of connection with the upper cross-bar 3, with plain squared portions 7, which are surmounted by spherical figures 8. The upper cross-bars 3 of the opposite end frame portions 1 are formed in their upper corners with spaced pairs of elliptical concavities 9. The design for the frame is completed by connecting the lower cross-bars 4 with a pair of parallel horizontal base-bars 10, formed in their upper outer corners with a series of angular indentations 11.

What I claim is—

The design for a cradle-frame herein shown and described.

In testimony that I claim the foregoing as my own I have hereto affixed my signature in the presence of two witnesses.

RIES W. HAGGARD.
